UNITED STATES PATENT OFFICE.

STANLEY KALBACH, OF WILDWOOD, NEW JERSEY.

ELECTRIC-LIGHT-CIRCUIT PROTECTOR.

SPECIFICATION forming part of Letters Patent No. 756,025, dated March 29, 1904.

Application filed May 12, 1902. Serial No. 106,883. (No model.)

To all whom it may concern:

Be it known that I, STANLEY KALBACH, a citizen of the United States, residing at Wildwood, in the county of Cape May and State 5 of New Jersey, have invented a new and Improved Electric-Light-Circuit Protector, of which the following is a full, clear, and exact description.

My invention relates to electric-light-circuit protectors—that is, to means for preventing interruption in the current fed to electric lamps caused by the disorder of one of the lamps.

It frequently happens where electric lamps, 15 and more particularly arc-lamps, are operated together in series that if the circuit of one lamp be left open it will have the effect of stopping the action of other lamps. It has been found by experience that most of the annoyance caused by electric lamps upon the street 20 is due to the electric-light leads. Much trouble of this kind is obviated by my device.

Reference is to be had to the accompanying drawing, forming a part of this specification, 25 in which the figure shows my invention as applied to an outdoor post of the kind used at the intersection of streets in a city.

The post 1 is provided with an arm 2, this arm being supported by a brace 3, substantially in the usual manner. The insulators 4 30 and the suspension-cord 6 are of the usual pattern. The arc-lamp is shown at 7. From a source of electrical supply 8 a wire 9 leads to the plate 10. To this plate are connected 35 the two wires 11 12. The wire 12 is connected with the electromagnet 13, and from this magnet a wire 14 leads to the metallic plate 15. From this plate the electrode 16 leads to the lamp, and from the lamp another electrode 17 40 leads to the binding-post 18, which is connected with the wire 19 and through the medium of this wire to the arc-lamps 20, 21, 22, and 23, and thence by return-wire 24 back to the source of electricity 8. The wire 11, which 45 is connected with the metallic plate 10, as above mentioned, is also connected with a resistance 25, this resistance being connected by a wire 26 with the armature 27 of the electromagnet 13. A contact-hook 28 is disposed 50 above the armature 27 and serves as a limiting-

stop for the upstroke of the same. A spring 29 serves as a tension member for restricting the armature 27, and this spring is adjustable by means of the threaded nut 30 in substantially the same manner as the spring of a telegraphic sounder.

The operation of my device is as follows: The current from the source of electricity flows through the wire 9 to plate 10, thence through wire 12 to magnet 13, thence through wire 14, 60 plate 15, electrode 16, lamp 7, electrode 17, binding-post 18, wire 19, lamps 20 21 22 23, and wire 24 back to the source from whence it started. This energizes the magnet 13, causing the armature 27 to be drawn downward contrary to the tension of the spring 29. The apparatus remains in the position described so long as the lamp 7 burns properly. If, however, either of the electrodes 16 or 17 is broken or the carbons of the lamp are misplaced or 70 for any other reason the circuit through the lamp is left open, the magnet 13 immediately relaxes the armature 27, which is thereupon drawn by the spring 29 into contact with the hook 28. The current from the plate 10 now 75 flows through wire 11, resistance 25, wire 26, armature 27, hook 28, binding-post 18, wire 19, lamps 20 21 22 23, wire 24, source of electricity 8, and wire 9 back to plate 10, thus completing the circuit.

8c

It will be noted that an accident to lamp 7 does not interfere with the proper operation of the other lamps, even though the lamps be all connected in series.

The resistance 25 should preferably be 85 equally balanced against the resistance offered by the magnet 13, the lamp 7, while in action, and the electrodes 16 17. For this purpose any resistance may be used, and of course the same may be rendered variable, if desired. 90 The circuit can be tested at any time through the metallic plates 10 and 15. It will be noted that the resistance is thrown into circuit at the same instant when the electromagnet and the lamp are thrown out of circuit.

95

By use of the apparatus above described much annoyance and danger may be obviated. Where electric lights are used in large cities, it frequently happens that on stormy nights a lamp may become disabled, and this causes 100

other lamps to give trouble or to be extinguished. It may not be convenient for a line-man to repair the lamp or to attend to the trouble, from which it follows that a considerable number of lamps may be thrown out of action by a cause otherwise trivial. By my system such annoyance may be avoided.

When the break is repaired or the trouble obviated, the circuit is automatically restored to its normal condition, so that the apparatus is ready for immediate use—that is to say, the path through the wire 11, resistance 25, wire 26, armature 27, and contact-hook 28 now becomes the path of highest resistance, so that the greater portion of the current passes through the magnet 13, electrodes 16 17, and lamp 7, thereby energizing the magnet and opening the shunt-circuit through the resistance and the armature. The fact that the normal circuit is self-restoring constitutes a considerable advantage, because the lineman or repairer merely repairs the break *per se* or obviates the local trouble and gives himself no concern as to the path of the current.

Having thus described my invention, I claim as new and desire to secure by Letters Patent—

The combination with an electric circuit,

and a plurality of arc-lamps in series in the circuit, of a protector for each lamp and its source of supply, a support for each lamp and protector, said protector being located between the support and the lamp and independent of the lamp and connected with the lamp by electrodes, said protector comprising an electromagnet with which one of the circuit-wires is connected, a pivoted armature for the magnet, a binding-post with which the other circuit-wire is connected, said post being provided with a contact extending into the path of the armature, one of said electrodes being connected with the lamp and magnet and the other with the lamp and binding-post, and a resistance connected with the armature and with the circuit-wire with which the magnet is connected, the resistance being proportioned to shunt enough current through the magnet to operate it when the lamp-circuit is complete.

In testimony whereof I have signed my name to this specification in the presence of two subscribing witnesses.

STANLEY KALBACH.
